DISPLAY RACK

Robert Patterson, St. Louis, Mo.

Application December 21, 1936, Serial No. 116,871

7 Claims. (Cl. 35—53)

This invention relates to display racks for flexible roofing. The principal objects of the present invention are to provide each face of such a rack or frame with a separate display panel of shingles or roofing, to provide for the easy assembly of such panels in the rack and their removal therefrom, to dispense with the use of separate fasteners and backing panels for the display panels, and to provide for strength, durability, simplicity and economy of construction. The invention consists in the display rack and in the construction, combinations and arrangements of parts hereinafter described and claimed.

In the accompanying drawings, which form part of this specification and wherein like symbols refer to like parts wherever they occur,

Fig. 1 is a top view of a display rack embodying my invention,

Fig. 2 is a view looking at one face of said rack,

Fig. 3 is a similar view looking at the opposite face thereof,

Fig. 4 is an end view of the rack,

Fig. 5 is an enlarged vertical section on the line 5—5 of Fig. 2,

Fig. 6 is a fragmentary horizontal section on the line 6—6 of Fig. 2,

Fig. 7 is a vertical section on the line 7—7 of Fig. 2,

Fig. 8 is a horizontal section on the line 8—8 of Fig. 2,

Fig. 9 is a view showing the top and side frame members in position to receive the display panels,

Fig. 10 is a perspective view of the top frame member,

Fig. 11 is a perspective view of the bottom frame member; and

Fig. 12 is a perspective view of one of the separable sections of a side frame member.

Referring to the accompanying drawings, my roofing display rack comprises a rectangular metal frame made up of a top member A, a bottom member B, side frame members C, and two display panels D of shingles mounted back to back in said frame.

The top member A comprises a downwardly opening longitudinal channel 1 provided along its top with an upstanding medial flange 2 having a suitable hand hole 3 formed therein. One side of the vertical top flange 2 of the top frame member is provided with a pair of horizontally spaced vertically disposed hook flanges 4 adapted to overlap and hold against said flange a card 5 that rests on the channel 1 and contains directions for applying the roofing material displayed on the

rack. Solid color samples 6 of roofing material are supported on the channel on the opposite side of the flange 4 and are held flatwise against said flange by prongs 7 struck therefrom.

The bottom frame member B is in the form of an upwardly opening channel having relatively deep end portions 8 adapted to straddle the lower end portions of the respective side frame members C.

Each side frame member C is made up of 10 separable duplicate sections 9 that cooperate to form an inwardly opening longitudinal channel 10 in said side frame member. These channels in the side frame members cooperate with the channels in the top and bottom frame members 15 to form one continuous channel around the opening in the frame formed by said frame members. The upper end portions 11 of the two sections 9 of each side frame member C extend above the channel of the top frame member and are offset 20 inwardly to bring said portions in contact flatwise with the upstanding top flange 2 of said top frame member. The overlapping ends of the top and side frame members are removably secured together by bolts 12 that extend through registering holes provided therefor in said ends. The lower ends of the respective side frame member sections terminate in extensions in the form of upwardly extending hooks 13; and said sections are provided on their opposing faces with a plurality of vertically spaced upwardly extending hooks 15 that are struck from openings formed in said sections. The portions of the sections that are overlapped by the end portions 8 of the bottom frame member B are provided with 30 struck-up projections 16 that seat within openings 17 provided therefor in said end portions. In assembling and disassembling the side and bottom frame members, the end portions 8 of the bottom frame member spring apart far enough 40 to ride over the projections 16 on the side frame members and thus permit said projections to snap into the openings 17 in said end portions of said bottom frame member.

As shown in the drawings, each of the display 45 panels D is made up of a series of shingles that are assembled in the same manner in which they are applied to the roof or side of a building. The shingles shown in the drawings are three-in-one strip shingles that extend across the frame 50 from side to side thereof with their end portions extending into the grooves in the side frame members and with the lower edge of the lower strip resting on the hooks 13 and with the lower edges of the other strips resting on the vertically 55

spaced hooks 15. The lower strip shingles of each panel rest in the channel of the bottom frame member B; and suitable starter strips 18 and filler strips 19 are interposed between said 5 bottom strips and rest in said channel and extend into the grooves in the side frame members C. The uppermost strip shingles of each panel have their upper marginal portions seated in the downwardly opening groove in the top frame 10 member A.

By the arrangement described, the two shingle display panels D fill the opening in the rack or frame and their edges are securely held in the groove of the surrounding frame. The two 15 panels may be made to display different shingle patterns and color combinations, while the different solid colors of rolled roofing are displayed by the samples mounted on the top frame member of the display. The construction dispenses 20 with the use of backing panels and securing nails for the two shingle display panels; and the display panels may be readily removed and replaced merely by removing one of the sections of each side frame member.

Obviously, the hereinbefore described display 25 rack admits of considerable modification without departing from the invention. Therefore, I do not wish to be limited to the precise constructions shown and described.

30 What I claim is:

1. A display rack comprising an open frame having an inwardly opening groove extending around the opening defined by said frame, and separate display panels mounted in said opening 35 with their marginal edges seated in said groove, said panels consisting solely of flexible roofing disposed back to back, whereby each of said panels constitutes a supporting panel for the other panel.

40 2. A display rack comprising an open frame having an inwardly opening groove extending around the opening defined by said frame, and separate display panels mounted back to back in said opening with their marginal edges fitting in said groove, each of said display panels consisting solely of overlapping flexible shingles and 45 constituting a supporting panel for the other panel.

50 3. A display rack for roofing comprising an open frame having an inwardly opening groove extending around the opening defined by said frame, and separate display panels mounted back to back in said opening with their marginal edges seated in said groove, each of said display panels 55 consisting solely of overlapping flexible shingles and constituting a supporting panel for

the other panel, said frame being provided above said opening with a hand hole to facilitate carrying said rack.

4. A display rack for roofing comprising an open frame having an inwardly opening groove 5 extending around the opening defined by said frame, separate display panels mounted back to back in said opening with their marginal edges seated in said groove, each of said display panels consisting solely of overlapping flexible shingles, 10 and means located in said groove entirely clear of said opening and affording vertical support for the lower edges of the overlapping shingles of the respective panels.

5. A display rack comprising an open frame 15 having an inwardly opening groove extending around the opening defined by said frame, and separate display panels mounted back to back in said opening with their marginal edges seated in said groove, each of said display panels 20 consisting solely of overlapping shingles, said frame being provided with a plurality of vertically spaced prongs located in said groove and affording vertical support for the lower edges of the 25 overlapping shingles of the respective panels.

6. A display rack comprising an open rectangular frame and separate display panels mounted back to back in the opening defined by said frame, each of said display panels consisting solely of overlapping flexible shingles and 30 constituting a supporting panel for the other panel, said frame comprising top, bottom and side frame members removably secured together at the corners of said frame.

7. A display rack comprising an open rectangular frame having an inwardly opening groove 35 extending around the rectangular opening defined by said frame, and separate rectangular display panels mounted back to back in said opening with their marginal edges seated in said groove, each of said display panels consisting solely of overlapping flexible shingles, said frame comprising top, bottom and side frame members having longitudinal channels along their 40 inner edges that cooperate to form said inwardly opening groove; each of said side frame members comprising a pair of separable sections that cooperate to form the longitudinal channel 45 therein and are removably held together and to the top and bottom frame members at the corners of the frame, each of said sections having vertically spaced inwardly extending portions that extend into said groove and support the lower edges of said shingles therein.

55 ROBERT PATTERSON.
